UNITED STATES PATENT OFFICE.

NATHAN KAUFMAN, OF MONTREAL, QUEBEC, CANADA.

COPY-HOLDER FOR TYPE-WRITERS.

1,203,354.

Specification of Letters Patent. Patented Oct. 31, 1916.

Application filed March 19, 1915. Serial No. 15,673.

To all whom it may concern:

Be it known that I, NATHAN KAUFMAN, a subject of the King of Great Britain, residing at Montreal, in the Province of Quebec and Dominion of Canada, have invented certain new and useful Improvements in Copy-Holders for Type-Writers; and I do hereby declare the following to be a full, clear, and exact description of the invention, 10 such as will enable others skilled in the art to which it appertains to make and use the same.

This invention relates to copy holders, designed more particularly for use by type-writer copyists, and one of the principal objects of the invention is to provide a device which can be readily connected to one side of the key-board of a typewriter for supporting copies in a convenient place to be 15 readily seen by the copyist.

Another object of the invention is to provide a copy holder of simple construction which can be connected to any form of typewriter and which will hold the copy firmly 20 in position and permit the sheet to be withdrawn without interfering with the remaining sheets of the copy, and which can be quickly attached to and detached from a typewriter machine.

30 The foregoing and other objects may be attained by means of the construction illustrated in the accompanying drawing, in which—

Figure 1 is a front elevation of a copy holder made in accordance with this invention and connected to the side rail of a key-board of a typewriter, the latter being shown in section. Fig. 2 is a similar view of the frame, showing the supporting plate 40 for the copy removed therefrom. Fig. 3 is a vertical sectional view taken on the line 3—3 of Fig. 1.

Referring to the drawing, the numeral 1 designates the side frame bar of a type-writer machine, and 2 designates an inverted U-shaped clamp comprising two parallel members 3 and 4, and a bolt 5 extends through the members 3 and 4 and through the bar 1 and is provided with a 50 nut 6 for holding it firmly in place. The clamp 2 is formed integrally with the frame

of the copy holder. Extending at right angles to the member 4 of the clamp is an arm 7, and bent vertically from the arm 7 is a supporting bar 8 having a horizontal top support 9 extending therefrom, diagonal braces 10 and 11 assist in rendering the frame rigid. Depending from the bar 9 are hanger members 12, said members being connected to the bar 9 by bolts 13 provided with nuts 14. The lower ends of the hangers 12 are provided with outwardly curved hooks 15. The copy holding plate or board 16 is supported upon the hooks 15, and is provided with an upturned flange 17 at its lower edge. At the upper edge of the plate or board 16 is a spring clip 18 for holding the copy firmly in connection with the board while the lower edge of the copy is supported by the flange 17. The plate or board 16 may be of sufficient height to hold the paper connected thereto by the clip 18 without the bottom edge reaching to the flange 17 if desired.

Various changes may be made in the details of construction without departing from the spirit and scope of the invention as defined in the claim.

What is claimed is:—

A copy holder comprising an inverted U-shaped clamp adapted to be attached to the frame of a typewriter, a horizontal arm connected to the lower end of one of the arms of said U-shaped member and extending at right angles therefrom, a vertical supporting bar connected to the outer end of said arm, a horizontal arm connected to the upper end of the vertical bar and extending outwardly therefrom, a brace bar connected at one of its ends the last named bar adjacent the outer end thereof, and its lower end connected to the vertical bar, a second brace bar connected to the vertical bar and its lower end to the first named horizontal bar for rigidly supporting the same, hanger members secured at one of their ends to the top horizontal bar at spaced distance apart and depending downwardly and outwardly therefrom, their lower ends being curved outwardly forming hooks, a copy holding board substantially rectangular in shape and having its lower edge curved upwardly and

resting upon the hooks of the depending hangers, the upper edge resting against the top supporting bar, a spring clip carried centrally of the upper longitudinal edge 5 thereof, said clip adapted to hold the top face firmly in connection with the board when in use, substantially as set forth.

In testimony whereof I affix my signature in presence of two witnesses.

NATHAN KAUFMAN.
